UNITED STATES PATENT OFFICE.

JOHN T. HUSTON, OF HENDERSON, TEXAS.

PEANUT-SHELLER.

1,178,075.

Specification of Letters Patent.

Patented Apr. 4, 1916.

Application filed June 3, 1915. Serial No. 31,952.

To all whom it may concern:

Be it known that I, JOHN T. HUSTON, a citizen of the United States, residing at Henderson, in the county of Rusk, State of Texas, have invented certain new and useful Improvements in Peanut-Shellers; and I do hereby declare the following to be a full, clear, and exact description of the invention, such as will enable others skilled in the art to which it appertains to make and use the same.

This invention relates to certain novel and useful improvements in a machine for shelling peanuts, and other nuts having thin, fragile, easily broken shells.

In the present instance it is my purpose to provide a machine which will embody the desired features of simplicity, efficiency and convenience, and which, embodying as it does, but relatively few parts, and these of the simplest construction, may be manufactured and marketed at a relatively low cost.

Another object of my invention is to provide a machine which may be easily attached to a suitable stand or table, and if desired, operated by hand for the purpose of breaking and removing the shells of the nuts.

Furthermore, I propose to provide a machine wherein the breaking and removal of the shell is accomplished by the contact or rubbing of the nuts against each other in the operation of the machine, so that the shells will be quickly broken and stripped to permit the kernels to fall therefrom, the particles of the shell and the kernels then passing out through openings in the foraminous plate forming a part of the machine.

With the above recited objects and others of a similar nature in view, my invention consists in the construction, combination and arrangement of parts set forth in and falling within the scope of the appended claims.

In the accompanying drawings: Figure 1 is a front view of a machine embodying my invention. Fig. 2 is a central vertical longitudinal sectional view taken therethrough, the rotating shaft and the operating handle therefor being shown partially in elevation. Fig. 3 is a view of the casing portion of the machine, with the foraminous plate removed and showing the grooved or corrugated plate.

In the present instance I have shown a hand operated machine wherein the power shaft is turned by means of a handle, but

it is, of course, to be understood that in place of this handle, any suitable form of power device may be used for operating the machine.

Referring now to the accompanying drawings in detail, the numeral 1 indicates the back of the machine, which in the present instance is in the form of a circular disk or plate, preferably of cast metal, the inner face 2 of this plate being provided with radially extending ribs or corrugations 3, although it is to be understood that this face of the plate may be roughened in any manner desired. In the present instance these corrugations or ribs 3 extend from the hub section 4 of the back plate 1 to the periphery thereof. In the machine shown herein, this rear or back plate or disk 1 is stationary, and is provided with a circumferential flange 5 constituting the circular wall of the casing. Preferably formed integral with and depending from the bottom section of the circular flange 5 is a clamping arm or standard 6 having its lower end formed with the bifurcated head 7 adapted to engage with the edge of a table, stand or the like. This clamping head 7 is provided with a suitable clamping screw 8, which is provided with the thumb piece 9 by means of which the screw may be tightened and loosened in the usual manner. It will, of course, be evident that when the clamping head is engaged with the edge of the table or stand, the screw may be tightened to clamp the machine firmly in position. Preferably cast or otherwise formed integral with the upper portion of the back of the rear disk 1 of the machine, is a hopper 10, the front wall of which is preferably inclined, as at 11. The bottom edge of the front wall 11 of the hopper is concaved as at 12 to provide for the proper fitting of the front plate or disk 13 of the machine, this disk constituting the front wall of the casing. The disk 13 is provided with a hub section 14 adapted to fit on the rotatable or power shaft 15, this power shaft extending through the hub 4 of the rear plate or disk 1, and the rear end of the shaft 15 is threaded as at 16 for the reception of the operating handle 17, suitable nuts 18 securing the handle against accidental detachment.

It will be noted that while the rear disk or plate 1 is stationary, in the present instance, the front disk or plate 13 being fast

with the shaft 15, is adapted to rotate therewith, the hub 4 of the rear disk or plate forming a bearing for this shaft 15. Furthermore, this front plate 13 is provided 5 with a series of slots 19 arranged in circular spaced rows. There may be any number of these rows of slots, and the slots may be arranged in any suitable manner and of any 10 approved design, size or character to accommodate the particular nuts intended to be shelled. In other words, I reserve to myself the right to use any foraminous or perforated plate. These perforations or 15 openings in the plate 13 are provided for the purpose of allowing the kernels of the nuts and the particles of broken shell resulting from the shelling operation to pass out to the exterior of the machine, yet the kernels may be readily separated from the 20 particles of shell. Furthermore, while I have in the present instance shown the corrugated or grooved disk or plate of the machine as stationary, and the perforated or foraminous plate or disk as rotatable, it 25 will be understood that this order may be reversed, and if desired the corrugated or grooved plate may be made to rotate, while the foraminous or perforated plate may be made stationary. It will also be understood 30 that although I have shown and described the clamping arm and the hopper as formed integral with the stationary plate, these parts may be made separate if desired.

From the above description, taken in connection with the accompanying drawing, the construction and operation of my improved machine will be readily apparent to those skilled in the art.

In order to shell the nuts, it is only necessary to deposit the same in the machine through the hopper 10, and then turn the handle in the usual manner. This will cause the shaft 15, with its plate 13 to revolve, and in the revolution of the plate the 45 shells of the nuts will be cracked and broken to permit the escape of the kernels. This cracking and breaking of the shells of the nuts results from the rubbing or contact of the nuts against each other and against the 50 wall of the disks, this breaking operation being facilitated and assisted by the fact that one of the walls is corrugated or ribbed to provide a roughened surface, while the other wall is provided with slots, the edges 55 or walls of which slots also assisting in breaking the shells of the nuts.

What I have herein shown and described

one particular embodiment of my invention, I wish it to be understood that I do not confine myself to all the precise details of construction herein set forth by way of illustration, as modification and variation may be made without departing from the spirit of the invention or exceeding the scope of the appended claims. 65

What I claim is:—

1. In a nut shelling machine, a nut receiving casing comprising a stationary wall, a shaft extending therethrough, a rotatable wall mounted on the shaft and rotatable 70 relative to the stationary wall, one of said walls having a grooved face, and the other of said walls having openings extending therethrough for the escape of material from the casing. 75

2. In a nut shelling machine, the combination with a support, a stationary disk mounted on the support and having corrugations formed on one face thereof, a shaft carried by the stationary disk, a second disk carried by the shaft and spaced apart from the first-mentioned disk, said second disk having a series of openings extending therethrough, a flange constituting a wall extending between the two disks, and 80 a hopper for supplying the nuts to be shelled to the space between the two disks. 85

3. The combination with a support, a stationary corrugated disk integral with the support and a hopper integral with the stationary disk, of a rotatable shaft journaled at the center of the stationary disk, a foraminous disk mounted on one end of the shaft and adapted to be rotated therewith and to coöperate with the stationary 90 disk to shell the nuts occupying the space between the disks, and means for rotating the shaft. 95

4. In a nut shelling machine, a nut receiving casing having two spaced walls, one 100 of said walls having a grooved face, the other of said walls having a series of openings therein for the escape of material, a shaft extending through both walls and upon which shaft one of the walls is mounted to rotate, and means for rotating the shaft. 105

In testimony whereof, I affix my signature, in the presence of two witnesses.

JOHN T. HUSTON.
